UNITED STATES PATENT OFFICE.

ADOLPH WUNDER, OF NEW HAVEN, CONNECTICUT, ASSIGNOR TO SARGENT & CO., OF SAME PLACE.

DESIGN FOR A LETTER-CLIP.

Specification forming part of Design No. **6,200**, dated October 8, 1872.

To all whom it may concern:

Be it known that I, ADOLPH WUNDER, of New Haven, in the county of New Haven and State of Connecticut, have invented a new Design for Letter-Clip; and I do hereby declare the following, when taken in connection with the accompanying drawing and the letters of reference marked thereon, to be a full, clear, and exact description of the same, and which said drawing constitutes part of this specification and represents, in—

Figure 1, a side view; Fig. 2, a top view of the under jaw; and in Fig. 3, a top view of the upper jaw.

This invention relates to a design for the article known as a letter-clip, and consists in the peculiar configuration and ornamentation of the parts, as shown in the accompanying drawing and as hereinafter described.

A is the lower part or jaw; B, the upper

part or jaw; each part in configuration, as shown respectively in Figs. 2 and 3. The lower part may be ornamented or not. The upper part B is ornamented with a plain edge, forming a paneled surface, and filled with tracery upon a matted surface, as seen in Fig. 3. These two parts may be used together or each in connection with another part, hence I do not confine my design to the two parts combined; but

I claim as my invention—

The design for the two parts A and B of a letter-clip, as described and shown in the accompanying drawing, whether used separately or together.

ADOLPH WUNDER.
